PACKAGE AND METHOD OF PACKAGING

Clarence J. Malhiot, Oak Park, Ill., assignor to
F. B. Redington Co, Chicago, Ill., a corporation
of Illinois

Application October 7, 1939, Serial No. 298,457

6 Claims. (Cl. 229—51)

The present invention relates to packages, particularly of the multiple wrapper type, and to methods of packaging.

It is a primary object of the invention to provide a package of the multiple wrapper type having opening means incorporated therein readily operable to sever or open all of the multiple wrappers whereby to expose or render accessible the wrapped article.

It is a further object of the invention to provide an opening structure for a multiple wrapper package which includes an opening element operable to sever or open a plurality of complete wrappers, and to completely sever or open the same by a single rotary manipulation.

Further objects of the invention are to provide an opening structure for packages of the foregoing type which will in no way impair the tight seal for the article provided by the multiple wrappers, and which will be operable to effect the opening operation regardless of the relative position of the overlapped edges of the wrappers, whether the sets of overlapped edges are on the same or different faces of the package, and whether they are in displaced or superposed relation.

Other objects of the invention are to provide improved methods for securing or anchoring the opening element to the wrappers, improved means for arranging the operable end of the opening element with respect to the adjacent wrapper portions, and improved means for insuring the initial tearing or rupture of the wrappers as the opening element is manipulated.

A still further object of the invention is to provide for the production of a package of the foregoing multiple wrapper type, and including an opening means of the type set forth, wherein the wrappers may be applied to the article to effect the wrapping thereof in sequence or simultaneously.

Various other objects, advantages and features of the invention will appear from the following specification when taken in connection with the accompanying drawings, wherein certain preferred embodiments of the invention are set forth for purposes of illustration.

In the drawings, wherein like reference numerals refer to like parts throughout:

Figure 1 is a perspective view illustrating the manner of placement of the opening element upon the inner wrapper in the production of a double wrapper package construction, in one form, in accordance with the principles of the invention.

Figs. 2, 3 and 4 illustrate successive steps in the wrapping of the inner wrapper about the article.

Fig. 5 shows the completed inner wrapper.

Figs. 6, 7 and 8 illustrate successive steps in the placement of the outer wrapper.

Fig. 9 illustrates the completed double wrapped package.

Figs. 10 and 11 are perspective and sectional views, respectively, of a modified form of construction wherein the operable end of the opening element is flush with the edge of the outer wrapper.

Figs. 12 and 13 illustrate successive steps in the making of a package of modified form, wherein the overlapped edges of the two wrappers lie in superposed relation upon the same package face.

Fig. 14 is a partial sectional view of the package of Fig. 13, more particularly illustrating the positions of the superposed overlapped wrapper edges.

Fig. 15 is a similar sectional view of a slightly modified form of construction.

Figs. 16, 17, 18 and 19 show successive method steps in the production of a package by the simultaneous application of the inner and outer wrappers, and

Fig. 20 illustrates the initial method step in the simultaneous application of inner and outer wrappers, but to produce a package of modified construction.

Referring more particularly to the drawings, and first to the embodiment illustrated in Figs. 1 to 9, in Fig. 1 there is shown an opening element 10 in its position of initial placement upon a wrapper 11 which is to form the inner wrapper member of the completed package. The wrapper 11 may be of any suitable wrapping material, such as paper or the like, but in the particular embodiment illustrated it is preferably of cellulosic material such as "Cellophane" whereby to impart maximum moisture proof protection to the wrapped article. Similarly the opening element 10 may be of any suitable material, and may be either in the form of a tape or a string, but preferably in the particular embodiment illustrated the opening element is also of "Cellophane," and preferably also of contrasting color to the wrapper so as to render it readily discernible.

The opening element is adhesively secured to the inner face of the wrapper, and preferably the element is adhesively secured to the wrapper along the entire length of contact between the

parts. Any suitable adhesive may be employed, one suitable adhesive being in the form of a Cellophane solvent which slightly attacks the surface of the Cellophane and produces a satisfactory sealing bond between the parts. The inner end 13 of the opening element, as shown, terminates flush with the edge 14 of the wrapper, whereas the outer end 15 of the element extends a predetermined distance beyond the opposite wrapper edge 16. The wrapper 11 is provided with short slits 17 and 18 arranged on either side of the opening element. These slits facilitate the initial tearing of the wrapper in a manner which will be more particularly hereinafter set forth.

In fabricating the package, the edge 14 of the wrapper is first folded over the article 19 which may for example be a pack or package of cigarettes or like article, in a manner best illustrated in Fig. 2. The article may directly engage the inner face of the wrapper and the opening element 18 superimposed thereon. The opposite end edge of the wrapper is then folded over onto the upper face of the package as illustrated in Fig. 3, the projecting portion or extension 15 of the opening element projecting beyond the associated package edge 20. The folding of the wrapper in the manner described provides a pair of overlapped wrapper edges on the upper face of the package, with the opening element extending therebetween. The engaging faces of the overlapped wrapper edges are adhesively secured along their entire length of contact whereby to form a moisture proof bond along the wrapper seam. Preferably the opening element is also adhesively secured to the upper wrapper face 21 along its length of contact therewith to insure the production of a moisture proof seal along the entire length of the overlapped wrapper edges. In other words the faces of the opening element or tape are adhesively secured to the adjacent wrapper faces at the juncture of the overlapped wrapper edges insuring the production of a moisture proof seal.

The end folds in the wrapper are produced in a suitable manner, as illustrated in Figs. 4 and 5. The side sections 22 and 23 of the wrapper ends are first folded against the end face of the article, and the top and bottom sections 24 and 25, respectively, are then folded into position against the end of the package as illustrated in Fig. 5. The engaging faces of the end folds are all adhesively secured together whereby to provide a moisture proof end seal for the package, and also to hold the end folds in place. The wrapper portions at both ends of the package may be similarly folded, the inner wrapper in its completed form being illustrated in Fig. 5.

After the completion of the inner wrapper, and the folding thereof around the article, an outer wrapper 30 is applied to the package as illustrated in Fig. 6. The outer wrapper may be of any suitable wrapping material, but in the particular embodiment illustrated it is preferably of "Cellophane," of a character similar to the inner wrapper. The outer wrapper is provided with a pair of slits 31 and 32 in the end edge 33 thereof, the slits being so positioned that they will lie on opposite sides of the opening element when the wrapper is folded into position around the package.

In folding the outer wrapper onto the package the edges 33 and 34 of the wrapper are first folded onto the upper and lower faces of the package in a manner illustrated in Fig. 7. The

edge 34 is then folded into engagement with the side face of the package, and the edge 33 brought into superimposed relation as indicated in Fig. 8, producing a pair of overlapped wrapper edges on the side face of the package. As previously stated, and as best indicated in Fig. 8, the slits 31 and 32 lie on opposite sides of extending end 15 of the opening element as the wrapper edge 33 is folded into position. As the edge 33 is folded downwardly, the end 15 of the opening element is folded downwardly into engagement with the side face of the package. The end is of sufficient length, however, that it extends beyond the package edge 35. The overlapped wrapper edges are adhesively secured along their entire contacting length, and the faces of the opening tape are also adhesively secured on either side to the contacting wrapper faces at the point of overlap whereby to provide and insure a moisture proof seal extending continuously along the entire side seam of the outer wrapper. The outer wrapper end folds 36, 37, 38 and 39 are then formed, as indicated in Fig. 9 and as previously described in connection with the end folding of the inner wrapper. The end folds are adhesively secured together along their faces of contact whereby to provide a second moisture proof end seal for the package. The end folds at both ends of the package may be similarly formed.

In operation, as the projecting end 15 of the opening element is grasped and unwound from the package, in a counter-clockwise direction as seen in Fig. 9, both wrappers will be opened or torn. If the unwinding movement of the opening element is continued for substantially one complete movement, both wrapper ends will be completely torn off or removed. The slits 31 and 32 facilitate the initial tearing of the outer wrapper as the opening element is pulled whereas the slits 17 and 18 facilitate the initial tearing of the inner wrapper. The positioning of the slits, together with the arranging of the opening element in embracing relation about the package, insures the production of a clean circumferential tear in both wrappers as the opening element is manipulated. The adhesive securing of the opening element, particularly to the inner face of the inner wrapper insures that the opening element will not be dislodged or merely slipped outwardly from the folds of the wrapper as it is pulled. Being anchored to the inner wrapper along its entire length, the pulling force exerted on the opening element results in the insured tearing of the wrapper.

It will be seen that the invention provides readily operable means for opening a double wrapped package. Both the inner and outer wrappers are complete enclosures for the article, producing a double moisture proof and protection seal therefor, and yet both wrappers may be readily opened or severed by the manipulation of a single opening tape, the wrappers being completely torn from the package by a single revolution opening movement of the tape. The opening element in no way interferes with the moisture proof characteristics of the package. To this end the opening element is sealed adhesively to the contacting wrapper portions at the overlapped wrapper edges thus maintaining the continuity of the sealed seam. The end 15 of the opening element extends beyond the edge of the package, thus facilitating the ready gripping of the opening element to effect the wrapper removing operation.

In Figs. 10 and 11 an embodiment of the in-

vention is illustrated which is similar to that previously described, except that the end of the opening element does not extend beyond the edge of the package. Also the overlapped outer edge of the outer wrapper in this instance lies substantially coincident with the edge of the package. More specifically, the extreme end of the opening element as indicated at 45 in this instance terminates at the edge 33 of the overlapped outer wrapper section. The edge of the wrapper is also, as illustrated, substantially coincident with the package edge. In certain instances, for example to facilitate packing or to avoid the inadvertent catching of the end of the opening element resulting in the inadvertent tearing of the wrapper, it may be desirable to terminate the end of the opening element substantially at the edge of the outer wrapper as illustrated in Figs. 10 and 11. Due to the presence of the slits 31 and 32 in the wrapper edge a tab portion 47 is in effect formed in the wrapper itself between the slits, facilitating the initial gripping of the opening tape. Accordingly the end of the opening tape can be readily gripped even though the tape end does not extend beyond the edge of the wrapper. The slits 31 and 32 thus provide means for permitting the use of a non-projecting opening element, while at the same time maintaining the ready gripping and operability of the opening structure.

In Figs. 12, 13 and 14 an embodiment of the invention is illustrated which is also generally similar to that first described, except that the overlapped edges of the inner and outer wrappers in this instance lie upon the same face of the package, and are in superposed relation. In most instances it is preferred to form the package as shown in Figs. 1 to 9 inclusive, wherein the overlapped edges of the inner wrapper and the overlapped edges of the outer wrapper are on different package faces, as this arrangement displaces the wrapper seams and imparts maximum protection and moisture proof characteristics to the package. However, in certain instances it may be desired to arrange the overlapped edges of the two wrappers on the same package face, in displaced or overlapped relation. The invention as set forth in Figs. 12, 13 and 14 provides for the incorporation of a readily operable opening structure for a double wrapper package wherein the overlapped edges of the two wrappers are in superposed relation upon the same package face.

In fabricating this form of package, after the arrangement and folding of the inner wrapper as previously described, the outer wrapper is applied to the package in the manner illustrated in Fig. 12. The edge 34 of the outer wrapper is in this instance folded onto the top face of the package, and as the wrapper edge is folded into position the extending end of the opening element will be reversely bent as indicated at 50 in Fig. 14. As the opposite wrapper edge 33 is then folded downwardly into position upon the top of the package, the opening element will again be reversely bent as indicated at 51 in Fig. 14. The opening element is made, if desired, of sufficient length so that it projects beyond the package edge as indicated at 52. It is to be noted that in this form of structure, not only are the slits 31 and 32 provided in the wrapper edge 33, but the wrapper edge 34 is also provided with slits 53 and 54 adapted to lie on opposite sides of the opening element and facilitate the initial tearing of the wrapper. The overlapped wrap-

per edges are adhesively sealed together and to the adjacent surfaces of the opening element whereby to provide a moisture proof seam, and the end folds of the package are made and sealed as previously described.

In operation as the end of the opening element is gripped and pulled, the slits 31 and 32 will provide for the initial tearing of the outer wrapper edge 33. The slits 53 and 54 will permit the tearing of the opposite wrapper edge 34 as the reverse fold 51 in the opening tape is straightened out. The slits 17 and 18 of the inner wrapper, Fig. 5, then facilitate the initial tearing of the inner wrapper as the opening element is further pulled, both wrappers being opened or severed upon the continued movement of the opening tape, as described with reference to the previous embodiments of the invention. It will be seen that the structure of Figs. 12, 13 and 14 provides for the ready opening of a double completely wrapped package wherein the overlapped wrapper edges are in superposed relation, the opening structure while being readily operable in no way interfering with the moisture proof or protection characteristics of the wrappers.

In Fig. 15 a structural embodiment of the invention is illustrated which is the same as that shown in Figs. 12, 13 and 14, except that the outer wrapper edge 33 is in this instance extended so that it lies upon the side face of the package. The wrapper edge 34 however, lies upon the top face of the package, as in Figs. 12, 13 and 14. In this form of structure, therefore, the overlapped wrapper edges lie upon two package faces, and due to the greater margin of overlap additional protection is provided. In this instance the opening element is of sufficient length so that its end projects beyond the lower edge of the package as indicated at 57. The form of structure shown in Fig. 15, wherein a greater margin of overlap is provided between the wrapper edges extending to two adjacent package faces, may in some instances be desired.

In Figs. 16, 17, 18, and 19 an embodiment is illustrated wherein the principles of the invention are applied to the simultaneous application of the inner and outer wrappers to the article, as distinguished from the sequential application of the wrappers as previously described. In this instance, the inner wrapper 11 with the opening element 10 secured thereto, as previously described in connection with Fig. 1, is brought into superimposed relation with the outer wrapper 30. The slits 17 and 18 in the edge 16 of the inner wrapper and the slits 31 and 32 in the edge 33 of the outer wrapper are in aligned relation on opposite sides of the opening element. In the formation of the package, the lower edges 14 and 34 are folded simultaneously or as a unit around the lower and side faces of the article 19, as illustrated in Fig. 17. However, the edge 34 of the outer wrapper is maintained in an upwardly projecting position, while the edge 14 of the inner wrapper is folded over into engagement with the top face of the article.

After the lower edge 14 of the inner wrapper has been folded into position, the upper inner wrapper edge 16 is folded downwardly onto the top of the article, the overlapped wrapper edges being adhesively secured together as previously described. As the edge 16 of the inner wrapper is folded downwardly onto the top of the article, the projecting portion of the opening element strikes the upstanding edge 34 of the outer wrapper, causing the end of the opening element to

become upwardly bent, as indicated at 68 in Fig. 17. As the edge 34 of the outer wrapper is then folded downwardly onto the top face of the article, as shown in Fig. 18, the projecting end of the opening element will be reversely bent as previously described with reference to the bend 58 in the embodiment illustrated in Fig. 14. The upper edge 33 of the outer wrapper is then folded into position upon the top face of the article as shown in Fig. 19, causing the projecting end 15 of the opening element to again be reversely bent, as described with reference to the reverse bend 51 of Fig. 14.

The overlapped edges of the outer wrapper are adhesively sealed, as previously described, and the projecting end 15 of the opening tape may be of such length that it projects beyond the edge of the package. The end folds of the package may be made by folding the two wrapper thicknesses together into the four end fold sections, but in the interest of greater protection and fluid tightness it is preferred to fold and adhesively secure the end sections of the inner wrapper and thereafter fold and adhesively secure the end sections of the outer wrapper whereby to provide two completely sealed and independent ends for the package.

It will be seen that the resulting package produced by the foregoing method is the same as that illustrated in Figs. 13 and 14, having superposed overlapped wrapper edges on the same face of the package. The operation of the opening element is the same as previously described, and to facilitate the tearing of the edge 34 of the outer wrapper, it is to be noted that the slits 53 and 54 are provided. The structural embodiment illustrated in Figs. 16, 17, 18, and 19 thus provides for the simultaneous application of the plural wrappers to the article while retaining the principles of the invention.

In the simultaneous application of the wrappers to the article, the type of package produced will be determined by the original placement or superposed positioning of the inner and outer wrappers relative to each other and to the article. Thus in Fig. 20, an arrangement is illustrated wherein the two wrappers 11 and 30 are longitudinally displaced a greater amount than in Fig. 16, and the placement of the wrappers with respect to the article is such that, when the wrappers are folded around the article in the manner previously described with reference to Figs. 16 to 19, incl., the overlapped edges of the inner wrapper will lie upon the upper face of the article, whereas the overlapped edges of the outer wrapper will lie upon the side face of the article, producing a package such as shown in Fig. 9.

It is to be noted that, as illustrated, the opening element is preferably arranged adjacent one end of the package so that the ends of the wrappers may be severed by manipulation of the opening element as described, while leaving the main body of the article still enclosed within the remaining wrapper portions.

It is obvious that various changes may be made in the specific embodiments and the various method steps heretofore set forth without departing from the spirit of the invention. Accordingly, the invention is not to be limited to the specific embodiments and method steps described, but only as indicated in the following claims.

The invention is hereby claimed as follows:

1. A package for articles comprising an inner wrapper arranged about an article and an outer

wrapper arranged about the inner wrapper, each of said wrappers having overlapping adhesively secured end folds and overlapping adhesively secured side edges whereby each of the wrappers is adapted to form a complete enclosure for the article, and an opening element extending substantially once around the package, the opening element comprising a strip which is interposed between overlapping adhesively secured side edges of both wrappers, the outer edge of the inner wrapper being notched on each side of said opening strip and closely adjacent the side margins of said strip, and at least one edge of the outer wrapper being notched on each side of said opening strip and closely adjacent the side margins of said strip, whereby as the opening strip is pulled both wrappers will be torn along the line determined by said strip.

2. A package for articles comprising an inner wrapper arranged about an article and an outer wrapper arranged about the inner wrapper, each of said wrappers having overlapping adhesively secured end folds and overlapping adhesively secured side edges whereby each of the wrappers is adapted to form a complete enclosure for the article, and an opening element extending substantially once around the package, the opening element comprising a strip which is interposed between overlapping adhesively secured side edges of both wrappers, the outer edge of the inner wrapper having weakened portions on each side of said opening strip intersecting the said edge and closely adjacent the side margins of said strip, and at least one edge of the outer wrapper having weakened portions on each side of said opening strip and closely adjacent the side margins of said strip whereby as the opening strip is pulled both wrappers will be torn along the line determined by said strip.

3. A package for articles comprising an inner wrapper arranged about an article and an outer wrapper arranged about the inner wrapper, each of said wrappers having overlapping adhesively secured end folds and overlapping adhesively secured side edges whereby each of the wrappers is adapted to form a complete enclosure for the article, and an opening element extending substantially once around the package, the opening element comprising a strip which is interposed between overlapping adhesively secured side edges of both wrappers, the outer edge of the inner wrapper being notched on each side of said opening strip and closely adjacent the side margins of said strip, and the outer edge of the outer wrapper being notched on each side of said opening strip and closely adjacent the side margins of said strip whereby as the opening strip is pulled both wrappers will be torn along the line determined by said strip.

4. A package for articles comprising an inner wrapper arranged about an article and an outer wrapper arranged about the inner wrapper, each of said wrappers having overlapping adhesively secured end folds and overlapping adhesively secured side edges whereby each of the wrappers is adapted to form a complete enclosure for the article, and an opening element extending substantially once around the package, the opening element comprising a strip which is interposed between overlapping adhesively secured side edges of both wrappers, the outer edge of the inner wrapper being notched on each side of said opening strip and closely adjacent the side margins of said strip, and both edges of the outer wrapper being notched on each side of said opening strip

and closely adjacent the side margins of said strip whereby as the opening strip is pulled both wrappers will be torn along the line determined by said strip.

5. A package for multi-sided articles comprising an inner wrapper arranged about an article and an outer wrapper arranged about the inner wrapper, each of said wrappers having overlapping adhesively secured end folds and overlapping adhesively secured side edges whereby each of the wrappers is adapted to form a complete enclosure for the article, and an opening element extending substantially once around the package, the opening element comprising a strip which is interposed between overlapping adhesively secured side edges of both wrappers, the outer edge of the inner wrapper being notched on each side of said opening strip and closely adjacent the side margins of said strip, and the outer edge of the outer wrapper being notched on each side of said opening strip and closely adjacent the side margins of said strip whereby as the opening strip is pulled both wrappers will be torn along the line determined by said strip, the overlapping side edges of the outer wrapper and the overlapping side edges of the inner wrapper being dis-

posed on angularly offset side faces of said package.

6. A package for multi-sided articles comprising an inner wrapper arranged about an article and an outer wrapper arranged about the inner wrapper, each of said wrappers having overlapping adhesively secured end folds and overlapping adhesively secured side edges whereby each of the wrappers is adapted to form a complete enclosure for the article, and an opening element extending substantially once around the package, the opening element comprising a strip which is interposed between overlapping adhesively secured side edges of both wrappers, the outer edge of the inner wrapper being notched on each side of said opening strip and closely adjacent the side margins of said strip, and both edges of the outer wrapper being notched on each side of said opening strip and closely adjacent the side margins of said strip whereby as the opening strip is pulled both wrappers will be torn along the line determined by said strip, the overlapping side edges of said outer wrapper being disposed on the same side of said package and in superposed relationship.

CLARENCE J. MALHIOT.
